LOCKSTITCH SEWING MACHINE

Fred Ashworth, Wenham, Mass., assignor to
United Shoe Machinery Corporation, Paterson,
N. J., a corporation of New Jersey

Application July 17, 1931. Serial No. 551,418

21 Claims. (Cl. 112—36)

The present invention relates to lockstitch sewing machines, and particularly to the devices embodied in such a machine for handling the locking thread.

8 In such machines, it has been proposed to pull off the required amount of locking thread by means of a thread outlet positioned eccentrically to the axis of the shuttle. In thus pulling off shuttle thread, however, the shuttle pulls against 16 the stitch lock, tending to dislodge it, and thus causing irregularities in the location of the stitch locks with relation to the surface of the work.

The principal object of the present invention is to overcome this defect in the operation of 18 lockstitch sewing machines in which the movement of the shuttle is utilized to pull off the required amount of locking thread for each stitch, and with this object in view, a feature of the invention contemplates the provision of a thread 20 lock between the shuttle and the work, arranged to be closed so as to hold the shuttle thread during the thread drawing movement of the shuttle.

In connection with the thread lock above referred to, the invention also contemplates the 25 provision of a thread lock for the shuttle thread against which the stitch is set. In the preferred form of the invention hereinafter specifically described, the same thread lock is utilized to lock the shuttle thread both while the shuttle thread 30 is being drawn from the shuttle, and while the shuttle thread is being drawn into the work to set the stitch. In its broader aspects, however, this feature of the invention is not limited to the use of a single thread lock for performing 35 both functions. Where a single thread lock is employed it is necessary to pull the thread which has been drawn from the shuttle through the thread lock before the thread lock is closed prior to the final setting of the stitch. To secure this 40 result, a feature of the invention contemplates the provision of means for drawing the slack shuttle thread, which has been pulled from the shuttle, through the thread lock before the lock is closed preparatory to the final setting of the 45 stitch. In the construction hereinafter specifically described, this thread drawing means consists of a thread finger arranged to act upon the shuttle thread between the thread lock and the work.

50 It is desirable that both the needle thread and the shuttle thread be released at the end of a sewing operation, in order to permit the work to be withdrawn from the machine without first severing the threads. It is not desirable, however, 55 that the shuttle thread lock be opened suffi-

ciently to wholly disengage the shuttle thread, because the withdrawal of the work from the machine under such circumstances would tend to pull the thread away from the lock, thereby necessitating the re-threading of the lock before commencing another sewing operation. In order to avoid such a situation, a feature of the invention contemplates the provision of means whereby the thread lock is opened at the end of a sewing operation only enough to permit 60 shuttle thread to be drawn therethrough without undue restraint while preventing the escape of thread from the lock as the work is withdrawn.

As well understood by those skilled in the art, 65 variations in thickness of work require corresponding variations in the length of shuttle thread drawn off for stitch formation, and similarly, variations in the feed of the work and variations in the depth to which the stitch lock is sunk require variations in the length of shuttle 70 thread drawn off. It is therefore desirable, in a machine in which the stitch is set against a shuttle thread lock, to provide means for adjusting the length of the shuttle thread drawn from the supply. To that end, a feature of the invention 75 consists in an eccentric outlet for the shuttle thread adjustable toward and from the axis of the shuttle.

Another feature of the invention consists in the provision, in a shuttle, wherein a thread holder is removably secured by a locking member, of a hollow spring-pressed plunger which serves both to secure the locking member in locking position and to impart tension to the shuttle thread.

Other features of the invention consist in the 85 construction, combinations and arrangement of parts hereinafter described and claimed, the advantages of which will be understood by those skilled in the art from the following description.

In the drawings illustrating the invention in its preferred form, Fig. 1 is a left side elevation of a machine embodying the several features of the invention; Fig. 2 is a right side elevation of the head of the machine; Fig. 3 is a rear elevation of the oscillatory shuttle and its associated 90 mechanism; Fig. 4 is a plan view of the shuttle thread lock, the thread finger for drawing thread through the lock and the actuating mechanism therefor, with the parts in the position in which they appear at the end of a sewing operation; Fig. 5 is a sectional elevation taken on line 5—5 of Fig. 4; Fig. 6 is a sectional elevation taken on line 6—6 of Fig. 4; Fig. 7 is a sectional elevation taken on line 7—7 of Fig. 4; Fig. 8 is a plan view 95 illustrating the same parts as in Fig. 4 with the 100

mechanism; Fig. 9 is a plan view of the shuttle thread lock, the thread finger for drawing thread through the lock and the actuating mechanism therefor, with the parts in the position in which they appear at the end of a sewing operation; Fig. 10 is a sectional elevation taken on line 5—5 of Fig. 4; Fig. 11 is a sectional elevation taken on line 6—6 of Fig. 4; Fig. 12 is a sectional elevation taken on line 7—7 of Fig. 4; Fig. 13 is a plan view 105 illustrating the same parts as in Fig. 4 with the 110

thread lock open, and with the thread finger at the limit of its operative movement; Fig. 9 is a sectional elevation taken on line 9—9 of Fig. 8; Figs. 10 and 11 are detail plan views of parts of the 5 mechanism for actuating the shuttle thread lock; Fig. 12 is a front view of the shuttle at the beginning of its advancing stroke taken on a plane at right angles to its axis of rotation, and illustrating in front elevation parts of its associated 10 stitch forming, work supporting and work feeding instrumentalities, and illustrating in sectional elevation, a portion of the work and a seam formed therein; Fig. 12 also illustrates the shuttle thread holder, and the shuttle thread 15 measuring means; Fig. 13 is a diagrammatic view illustrating the shuttle at the top of its advancing or loop taking stroke, and illustrating, in front elevation, parts of its associated stitch forming, work supporting and work feeding instrumentalities, 20 also illustrating, in sectional elevation, a portion of the work and a seam formed therein; Fig. 14 is a view similar to Fig. 13 illustrating the needle at the limit of its advancing stroke and the shuttle at the limit of its loop taking stroke; 25 Fig. 15 is a view similar to Figs. 13 and 14 illustrating the needle nearing the limit of its retracting stroke and the shuttle nearing the limit of its reverse stroke; Fig. 16 is a sectional elevation of the shuttle thread clamp illustrating a 30 portion of thread therein, the movable clamping member being in its partially closed position which occurs when the shuttle is in the position illustrated in Fig. 13; Fig. 17 is a detail sectional elevation of the shuttle thread clamp with the movable clamping member in its closed position which occurs when the shuttle is in the position 35 illustrated in Fig. 13; Fig. 18 is a detail sectional elevation of the shuttle thread clamp with the movable clamping member in its open position which occurs when the shuttle is in the position 40 illustrated in Fig. 14; Fig. 19 is a detail sectional elevation of the shuttle thread clamp with the movable clamping member in its closed position which occurs for the second time when the shuttle 45 is in the position indicated in Fig. 15; Fig. 20 is a detail sectional elevation of the shuttle and thread holder taken on line 20—20 of Fig. 12; and Fig. 21 is a detail sectional elevation of the shuttle and thread holder similar to Fig. 20 illustrating 50 the parts in position for threading.

Except as hereinafter described, the machine illustrated in the drawings is the same in the construction and arrangement and mode of operation of its various parts as the machine disclosed in the application of Bernard T. Leveque, for a lockstitch sewing machine, filed February 18, 1927, Serial No. 169,203.

The machine comprises a column 30 in the lower portion of which is mounted an electric 60 motor 32 by which the operating parts of the machine are driven. The main cam shaft, or as it may conveniently be termed, the sewing shaft is indicated at 34, and is journaled in the upper portion of the column. The sewing shaft is driven from the motor through a clutch 36, horizontal shafts 38 and 40 in the base of the machine, and a vertical shaft 42. The clutch 36 is controlled from a treadle lever 44 by means of which the clutch may be actuated to connect and 65 disconnect the shafts 38 and 40 from the source of power.

The shoe supporting horn is indicated at 46, and is provided at its tip with a whirl of usual construction which is driven through suitable 70 connections from the vertical shaft 42 as dis-

closed in the Leveque application above referred to.

The straight hook needle 48 and the discoidal shuttle 50 are actuated from the sewing shaft 34 in the same manner as in the machine of the Leveque application. The connections between the sewing shaft and needle comprise a crank pin offset from the forward end of the sewing shaft, a slotted lever 52 engaged by the pin, a needle actuating lever 54, a latch 56 connecting the slotted lever and the needle actuating lever, and a link connecting the needle actuating lever to the needle bar, 58. The shuttle is driven from the needle actuating lever 54 through a link which connects a downward extension from the hub of the lever to the upwardly extending arm of the shuttle actuating gear segment 60. The latch 56 is actuated from the starting and stopping treadle 44 on stopping the machine in the same manner as in the machine of the Leveque application, the release of the needle actuating lever 54 by the latch 56 taking place at that point in the cycle of operations when the needle reaches the limit of its retracting stroke.

A loop spreader which opens the needle loop 100 to facilitate the entry of the shuttle beak is indicated at 78, and consists of a suitably bent arm or finger secured to the forward end of a carrier bar 80, as disclosed in the applicant's pending application for a shoe sewing machine filed 105 February 9, 1929, Serial No. 338,756. To actuate the loop spreader so as to engage one side of the needle loop and separate it from the other side of the loop, the carrier bar 80 is supported by two parallel motion links 82 pivotally mounted at 110 their inner ends upon a bracket 84, forming that portion of the machine frame in which the shuttle driver shaft 36 is mounted. The links 82 are oscillated by a block 88 pivotally mounted upon the pivot shaft of the shuttle actuating gear segment 60 and rigidly connected to the gear segment and a suitably shaped cam groove is formed in the block 88 which is engaged by a stud projecting upwardly from the rear link 82. In order to provide clearance for a cam slide 168, herein-after described, that portion of the carrier bar 80 extending between the ends of the parallel motion links is upwardly offset, as illustrated in Fig. 2.

The shuttle of the illustrated machine comprises a discoidal shuttle casing 90, the rear end 115 of which is closed and the forward end of which is open to receive a thread holder, as illustrated in the applicant's pending application for a sewing machine shuttle, filed May 1, 1930, Serial No. 448,909. The thread holder consists of a cylindrical thread case 92, the rear end of which is open to permit the insertion of a cop of thread 120 while the holder is removed from the shuttle, and the front end of which, when the thread case is in position in the shuttle, forms a closure for the open end of the shuttle casing. From the closed end of the thread holder casing, a hollow stud 94 projects inwardly so as to form a central support for the inserted thread cop, and a central thread passage for the shuttle thread opening on 125 the forward end of the thread holder casing.

In order to lock the thread case securely in position in the shuttle casing 90 while permitting its ready removal, locking devices are provided as disclosed in the applicant's pending application for a sewing machine shuttle filed May 1, 1930, Serial No. 448,910. The locking devices comprise a flange 96 projecting radially from the inner end of the thread case 92 and adapted to engage a slot formed in the inner wall of 130

the shuttle casing, and the arm 98, the free end of which is arranged to engage a groove 100 formed in the shuttle casing diametrically opposite the end of the slot which receives the flange 96. To permit the arm 98 to be moved into and out of engagement with the groove 100, it is mounted upon a slide 102 which is arranged to move in the diametrically arranged guideway 104 formed in the outer end of the thread case 92. In order to facilitate threading, the arm 98 is pivotally mounted upon the slide 102, thus permitting the arm to be swung outwardly into the position indicated in Fig. 21. The arm 98 is held in locking position by the engagement of the hollow plunger 106 within the opening 108 formed in the arm 98. The hollow plunger 106 is yieldingly held in locking position by the compression spring 110 positioned within the hollow stud 94, and held between an inwardly extending flange formed in the inner end of the hollow stud and a shoulder 112 formed in the plunger 106. In order to permit the arm 98 to be readily unlocked, a slot 113 is formed in the plate 114 for the insertion of an unlocking tool.

In accordance with the feature of the invention relating to the provision of an eccentric outlet for the shuttle thread, adjustable toward and from the axis of the shuttle, the segment plate 114 is pivotally mounted upon a stud projecting upwardly from the arm 98 and has the thread eye 116 formed therein. To secure the plate 114 in adjusted position, the set screw 118 is passed through the slot 120 formed in the plate 114 and received within a tapped hole formed in the extension 122 of the arm 98. The disengagement of the plate 114 from its pivot is prevented by means of a tongue 124 formed in the plate 114 for engagement with a groove 126 formed at the base of the shoulder 128 formed in the arm 98. The shoulder 128 is adjacent the plate 114, and is made substantially flush therewith in order to present an even surface to the thread loop as the shuttle passes through it. To prevent interference between the set screw 118 and the thread loop as the shuttle passes therethrough, the plate 114 is recessed adjacent the slot 120 sufficiently to permit the set screw to be positioned with its head in flush relation to the plate 114.

In accordance with a feature of the invention, tension is applied to the shuttle thread by compressing the thread between the spring-pressed plunger 106 and the inner surface of the plate 114 as the thread is drawn from the thread case 92. Thus the plunger 106 performs the double function of locking the arm 98 and imparting tension to the shuttle thread, thereby obviating the provision of additional devices for imparting the desired tension to the thread.

In accordance with the feature of the invention relating to the provision of a thread lock between the shuttle and the work, a bracket 130 constituting the fixed locking member of the thread lock, is secured to the shuttle raceway 132 by means of the bolt 134, and is held against rotation by means of a tongue and groove connection 136 of ordinary construction. The bracket 130 extends downwardly from its connection with the raceway 132 on an arc substantially coincidental with the periphery of the raceway, and at its lower extremity is provided with a horizontal slot 138 located in vertical alignment with the axis of the shuttle. The movable locking member of the thread lock consists of the locking arm 140 secured to the carrier plate 142 slidably mounted between the supporting plates

144 and 146 and guided by the plate 148 arranged to fit within a rectangular opening formed in the carrier plate 142, the plates 144, 146 and 148 being secured to the under surface of the shuttle supporting bracket by means of the screws 150 as illustrated in Figs. 4 to 10 inclusive. The forward end of the locking arm 140 is constructed and arranged to enter the slot 138 formed in the bracket 130, and has a thread engaging notch 152 formed therein. The locking arm 140 is actuated to lock the thread between the notch 152 and the slot 138 formed in the bracket 130 when the thread eye 116 is at the lower extremity of its movement, and holds the thread thus locked until the thread eye 116 has been carried, by the oscillation of the shuttle, to the upper limit of its movement.

In order to make the shuttle thread drawn off by the thread eye 116 available for stitch formation, it is desirable, as has been stated, to provide means for drawing the slack shuttle thread through the thread lock. A feature of the invention consists, therefore, in a thread finger constructed and arranged to engage the shuttle thread between the thread lock and the work and to draw aside a bight of thread sufficient in extent to take up the slack shuttle thread measured off by the eccentric thread eye, the extent of movement of the thread finger being adjustable to accommodate it to adjustments of the thread eye. As illustrated, the thread finger consists of a lever 154 pivotally mounted at 156 in a lateral extension of the supporting plate 144, said lever extending downwardly to position it between the locking arm 140 and the work, and extending laterally from its pivot to a position beneath the locking arm 140, then extending forwardly to bring the end of the arm into thread engaging position, as illustrated in Fig. 8. To insure the proper engagement of the thread finger with the thread, a thread engaging hook 158 is formed in the free end thereof. The throw of the thread finger may be limited by the screw 155 mounted in a tapped hole in the thread finger and arranged to abut the supporting plate 146. The throw of the thread finger may be adjusted by changing the position of the screw 155 therein, a locking nut being provided to secure the screw in adjusted position. In drawing slack thread through the thread lock, a thread finger 154 draws the thread against a projection 160 from the locking arm 140, which projection extends outwardly from the arm 140 at one side of the thread engaging notch 152. To insure the engagement of the thread with the projection 160, the projection is made long enough to prevent its complete removal from the slot 138 during the unclamping movement of the arm 140.

The present invention contemplates the provision of a thread lock for the shuttle thread 135 against which the stitch is set. As herein illustrated, the stitch is set against the same thread lock which holds the thread during the thread measuring operation, although, as has been stated, the invention in its broader aspects is not limited to the use of a single thread lock for performing both locking operations.

As in the machine of the Leveque application above referred to, the shuttle goes through the needle loop during the advancing or work piercing stroke of the needle, and the stitch is set by the shuttle as the shuttle reaches the top of its advancing or loop taking stroke. The eccentric thread eye 116 pulls off shuttle thread during the reverse stroke of the shuttle, and 150

- the thread so pulled off remains between the thread eye and the thread lock during the succeeding advancing stroke of the shuttle, and at the end of the advancing stroke the thread finger 154 draws through the thread lock, the slack shuttle thread between the thread lock and the thread eye, the thread eye at this time being positioned at the lower extremity of its movement, as illustrated by Fig. 14. During the succeeding 10 reverse stroke of the shuttle, the thread finger 154 is returned to its inoperative position, and the shuttle thread between the thread lock and the work is left slack, as illustrated by Fig. 15. As the shuttle goes through another advancing 15 or loop taking stroke, this slack is taken up and the stitch lock is sunk a definite distance into the work, which distance is determined by the length of shuttle thread pulled off by the eccentric thread eye (see Fig. 13).
- 20 At the end of a sewing operation, the operator may desire to withdraw the work from the machine before severing the shuttle thread, and it is desirable to enable the operator to withdraw the work without exercising any particular care 25 to prevent the escape of the shuttle thread from its position between the bracket 130 and the locking arm 140. To that end, a feature of the invention consists in locating the locking arm 140, at the end of a sewing operation, in the position indicated by Fig. 4, wherein the thread is 30 free to pass through the thread lock, but is held against lateral movement relatively thereto.
- 35 The mechanism for actuating the locking arm 140 and the thread finger 154, as herein illustrated, comprises the compression springs 162 and 164 for imparting clamping movement to the arm 140, the contractile spring 166 for imparting thread engaging movement to the thread finger 154, and the cam slide 168 constructed and arranged to impart unclamping movement to the locking arm 140, and to impart return movement to the thread finger 154. The compression springs 162 and 164 are located, respectively, within the slots 170 and 172 formed in the carrier plate 142 upon which the locking arm 140 is mounted, and are seated against the forward extremities of said notches. It is desirable that the rear ends of the compression springs be seated 40 against the supporting plates 144 and 146, in order that they may impart a forward motion to the plate 142 and the locking arm 140. To that end, grooves 174 and 176 are formed in the supporting plates 144 and 146, respectively, as illustrated in Figs. 6 and 7, which grooves are coincident with the slots 170 and 172, respectively, and terminate at their rear ends in shoulders which operate to limit the rearward movement 45 of the compression springs. The contractile spring 166 connects the rearwardly and outwardly extending end of the thread finger 154 to the supporting plate 144, connections for the contractile spring comprising the bolts 178 and 180 secured in the thread finger 154 and the carrier plate 142, respectively, said bolts being grooved 50 at their threaded ends for the reception of the contractile spring. The cam slide 168 imparts unclamping movement to the locking arm 140 through the operation of the cam surface 182 upon the cam roll 184 rotatably mounted on the 55 extended head portion of the bolt 180. In order to provide clearance for the movements of the bolt 180, an opening 185 is formed in the plate 146. The relative position of the cam surface 182 and the cam roll 184 with the thread lock open is 60 illustrated by Fig. 8, and the relative position of 65 70 75

the cam roll and cam surface at the end of a sewing operation is illustrated by Fig. 4. The cam slide 168 imparts return movements to the thread finger 154 by the operation of the cam surface 186 upon the cam roll 184 rotatably mounted on the 80 extended head portion of the bolt 178.

In order to operate the lock arm 140 and thread finger 154 in timed relation to the operation of the shuttle, the cam slide is actuated from the shuttle actuating gear segment 60 through the 85 pinion 190 secured to the shuttle driver shaft, which in turn meshes with the rack surface 192 formed in the cam slide 168. The cam slide is mounted for sliding movement in guides formed by a cross bar 194, on the plate 148, which engages a longitudinal groove 196 in the inner surface of the cam slide and by a portion of the supporting plate 144 which extends over one edge of the slide.

The nature and scope of the invention having 95 been indicated, and a machine embodying the several features of the invention having been specifically described, what is claimed as the invention is:—

1. A lockstitch sewing machine having, in combination, a hook needle, a shuttle, a thread lock positioned between the shuttle and the work and operative while shuttle thread is being drawn from the supply.

2. A lockstitch sewing machine having, in combination, a hook needle, a shuttle, a thread lock positioned between the shuttle and the work and operative while shuttle thread is being drawn from the supply, and means positioned between the thread lock and the work for drawing slack shuttle thread through the thread lock.

3. A lockstitch sewing machine having, in combination, a hook needle, a shuttle, a thread lock positioned between the shuttle and the work and operative while shuttle thread is being drawn 115 from the supply, and a thread finger positioned between the thread lock and the work for drawing slack shuttle thread through the thread lock.

4. A lockstitch sewing machine having, in combination, a hook needle, a discoidal shuttle having an eccentric thread outlet formed therein, a thread lock positioned between the shuttle and the work and operative while shuttle thread is being drawn from the supply by the shuttle.

5. A lockstitch sewing machine having, in combination, a hook needle, a discoidal shuttle having an eccentric thread outlet formed therein, a thread lock positioned between the shuttle and the work and operative while shuttle thread is being drawn from the supply by the shuttle, and 130 means positioned between the thread lock and the work for drawing slack shuttle thread through the thread lock.

6. A lockstitch sewing machine having, in combination, a hook needle, a discoidal shuttle having an eccentric thread outlet formed therein, a thread lock positioned between the shuttle and the work and operative while shuttle thread is being drawn from the supply by the shuttle, and a thread finger positioned between the thread 140 lock and the work for drawing slack shuttle thread through the thread lock.

7. In a lockstitch sewing machine, the combination with a hook needle, a shuttle and devices cooperating therewith in forming a stitch 145 to pull thread from the shuttle and pull on the needle thread against the resistance of the shuttle thread to set the stitch, of means for locking the shuttle thread between the shuttle and the work while the shuttle thread is being pulled 150

- from the supply and while the stitch is being set.
8. A lockstitch sewing machine having, in combination, a hook needle, a shuttle, a thread lock positioned between the shuttle and the work and closed while shuttle thread is being drawn from the supply, and means for partially opening the thread lock after the completion of a sewing operation.
9. A lockstitch sewing machine having, in combination, a hook needle, a shuttle, a thread lock positioned between the shuttle and the work against which shuttle thread is drawn from the supply, and against which the stitch is set.
10. A lockstitch sewing machine having, in combination, a hook needle, a shuttle having an eccentric thread outlet formed therein, a shuttle thread lock positioned between the shuttle and the work, a thread finger positioned between the thread lock and the work, means for actuating the shuttle to cause the eccentric thread outlet to draw shuttle thread from the supply against the thread lock, then to set the previous stitch against the thread lock, means for then opening the thread lock, and means for then actuating the thread finger to draw through the thread lock the shuttle thread measured off by the eccentric shuttle thread outlet.
11. A lockstitch sewing machine having, in combination, a hook needle, a shuttle, a thread lock positioned between the shuttle and the work and operative while shuttle thread is being drawn from the supply, means positioned between the thread lock and the work for drawing slack shuttle thread through the thread lock comprising a lever pivoted on the machine frame having a thread engaging surface formed therein, and means for varying the limit of operative movement of the lever.
12. A lockstitch sewing machine having, in combination, a hook needle, a shuttle, a thread lock positioned between the shuttle and the work, means for holding the thread lock closed as shuttle thread is drawn from the supply and as the stitch is set, and means for partially opening the thread lock at the end of a sewing operation.
13. A lockstitch sewing machine having, in combination, a hook needle, a shuttle, a shuttle thread lock positioned between the shuttle and the work, a thread finger positioned between the thread lock and the work, a shuttle driver, a pinion secured thereto, a rack positioned to mesh with the pinion, a cam formed in the rack, operative connections between the cam and the thread lock for actuating the lock, a second cam formed in the rack, and operative connections between the second cam and the thread finger for actuating the finger.
14. A lockstitch sewing machine having, in combination, a hook needle, a shuttle, a shuttle thread lock positioned between the shuttle and the work, a thread finger positioned between the thread lock and the work, a shuttle driver, a pinion secured thereto, a rack positioned to mesh with the pinion, a cam formed in the rack, and operative connections between the cam and the thread lock for actuating the lock.
15. A shuttle for shoe sewing machines comprising a shuttle casing, a thread holder, a locking member for removably securing the thread holder within the shuttle casing, and a plate ad-
- justably secured to the locking member having a thread outlet formed therein adjustable toward and from the axis of the shuttle by the adjustment of the plate.
16. A shuttle for shoe sewing machines comprising a discoidal shuttle casing having an open end, a removable thread holder comprising a cylindrical casing having an end forming a closure for the open end of the shuttle casing, a locking member for removably securing the thread holder within the shuttle, and a plate adjustably secured to the locking member provided with a thread eye adjustable toward and from the axis of the shuttle by the adjustment of the plate.
17. A shuttle for shoe sewing machines comprising a shuttle casing, a thread holder, a locking member for removably securing the thread holder within the shuttle casing, and a plate pivoted on the locking member provided with a thread outlet adjustable toward and from the axis of the shuttle by a pivotal movement of the plate.
18. A shuttle for shoe sewing machines comprising a discoidal shuttle casing having an open end, a removable thread holder comprising a cylindrical casing having an end forming a closure for the open end of the shuttle casing, a hollow stud extending inwardly from the end of the thread holder and forming a passage for conducting thread out of the thread holder, a locking member for removably securing the thread holder within the shuttle casing, means for securing the locking member in locking position comprising a hollow spring pressed plunger positioned in the hollow stud, a plunger engaging surface formed in the locking member, and means for applying tension to the shuttle thread comprising a thread engaging surface formed in the plunger, and a cooperating thread engaging surface formed in the locking member.
19. A lockstitch sewing machine having, in combination, a hook needle, a discoidal shuttle having an eccentric thread outlet formed therein, a needle lever and connections for actuating the needle, connections between said lever and the shuttle for oscillating the shuttle, and a shuttle thread lock positioned between the shuttle and the work and operative while shuttle thread is being drawn from the supply by the shuttle.
20. A lockstitch sewing machine having, in combination, a hook needle, an oscillatory discoidal shuttle having an eccentric thread outlet formed therein, means for actuating the needle and shuttle timed to cause the shuttle to pass through the needle loop during the advancing stroke of the needle, and a shuttle thread lock positioned between the shuttle and the work and operative while shuttle thread is being drawn from the supply by the shuttle.
21. A lockstitch sewing machine having, in combination, a hook needle, an oscillatory discoidal shuttle having an eccentric thread outlet formed therein arranged to draw shuttle thread from the supply during the reverse stroke of the shuttle, a needle lever and connections for actuating the needle, and connections between said lever and the shuttle for actuating the shuttle timed to cause the shuttle to pass through the needle loop during the advancing stroke of the needle.

FRED ASHWORTH. 145
